UNITED STATES PATENT OFFICE

2,545,108

CANNED LIQUID DISPENSER

Israel Putnam, Jr., Sayre, Pa.

Application May 12, 1947, Serial No. 747,457

2 Claims. (Cl. 222—86)

1

The invention relates to a dispenser, and more especially to an opener and dispenser for canned liquids.

The primary object of the invention is the provision of a structure of this character, wherein canned liquid can be carried thereby, and such can opened for the dispensing of its content with ease and dispatch, the structure being novel in its make-up and unique in the assembly of its parts, thus handy for use.

Another object of the invention is the provision of a structure of this character, wherein the opener for the can or other like receptacle is removable and is mounted in a novel manner for detachment, while the body of such structure is sectional, it being made from plastic material, although it may be made from any other suitable selected material or materials, and the can for the liquid is readily and easily introduced and removed, as the occasion may require.

A further object of the invention is the provision of a structure of this character, wherein its pouring spout is adaptable for a closure cap which is removably fitted in place for closure sealing, the body of the structure being such as to accommodate cans or the like of different sizes, the can or the like being air vented on the opening thereof when placed in the structure for easy dispensing of content.

A still further object of the invention is the provision of a structure of this character, which is simple in its make-up, thoroughly reliable and efficient in operation, strong, durable, neat and attractive in appearance, susceptible of various uses, compact, readily and easily handled, possessed of few parts, readily and easily assembled with dispatch, and inexpensive to manufacture.

With these and other objects in view the invention consists in the features of construction, combination and arrangement of parts, as will be hereinafter more fully described, illustrated in the accompanying drawings, which disclose the preferred embodiment of the invention, and pointed out in the claims hereunto appended.

In the accompanying drawings:

Figure 1 is a side elevation of the structure in accordance with the invention.

Figure 2 is a vertical sectional view taken approximately on the line 2—2 of Figure 1 looking in the direction of the arrows.

Figure 3 is an elevation looking toward the inner face of one of the sections of the body of the structure.

Figure 4 is a fragmentary top plan view of the structure.

Figures 5 and 6 are fragmentary sections

2

showing connection details of the punches to the top, at the spout and vent ends, respectively.

Similar reference characters indicate corresponding parts throughout the several views in the drawings.

Referring to the drawings in detail, A designates generally the structure in its entirety, and comprises a sectional or two-part body, the parts being identified at 10 and 11, respectively, they being identical and match one another at the meeting edges 12 when abutting one with the other, to provide a receiving chamber 13, as created by the hollow formation of such parts of said body. The sections or parts 10 and 11 are preferably made from plastic material, although the same can be made from any suitable selected material or materials.

The body at its bottom is fully open, while the top crown of the said body is domed or upwardly arched as at 14, while at the meeting side edge of the section or part 10 of the body is a bead 15, which overlaps the side edge of the section or part 11 adjacent thereto and counterseats in a companion channel 16 in the latter, so that the inner surface of the body will be smooth for a flush joint between the sections or parts 10 and 11, respectively.

Immediately beneath the domed or arched top crown at diametrically opposite areas concurrent with the meeting edges 12 of the sections or parts 10 and 11 of the body are socketed webs 17, which create head shoulders of approximately sector formation, the sockets 18 being located to intersect the joint between the sections or parts 10 and 11, and one has interfitted therewith a tubiform outwardly tapered punch forming an opener 19, which has a beveled outer cutting tip 20, while in the other socket 8 is a corresponding punch 21, which forms a vent hole in a can, denoted generally at B, containing liquid to be dispensed in the use of the structure A. The webs have formed therein upwardly divergent passages 22 and 23, respectively, the former being for dispensing purposes, while the passage 23 is an air inlet-vent passage.

The domed or arched crown 14 about the passage 22 is formed with a boss 24 on which is detachably fitted a pouring spout 25, while removably engaged in the passage 23 is a closure cap 26, it having a central stopper formation 27 which is insertable in the said passage 23 to effect a plug thereto.

Detachably threaded at 28 onto the open bottom of the body constituted by the sections or parts 10 and 11, is a cup-shaped bottom closure 29, which has arranged therewith a coiled spring

30, which acts against the bottom of the can B to hold the same in place within the chamber 13, and this spring adapts different sizes of cans to the said structure A, as should be obvious when placed within the latter.

The body formed by the parts or sections 10 and 11 is provided with companion matched loop handle portions 31, which join or abut each other on the uniting of the said sections or parts together.

The punches 19 and 21, respectively, are removable from the sockets 18 on the opening of the joint between the sections or parts 10 and 11 of the body, this joint being separable in any suitable manner. These punches 19 and 21 are 15 preferably made from stainless steel, although they can be made from any other suitable material or materials.

The structure A is pressed over the can B of liquid which is introduced through the open bottom of the body constituted by the parts or sections 10 and 11, when the bottom closure 29 is detached, the opener 19 being adapted to penetrate the top of the can B, while the punch 21 pierces such top to provide an air vent therein, and thereafter the bottom closure 29 is attached to the body for retaining the can B in the chamber 13 thereof, the spring 30 being adapted to take up slack between the body and can, as should be apparent. This spring 30 also 25 snugly positions the can B within the structure A.

What is claimed is:

1. A device of the kind described, comprising a central longitudinally split container-receiving body dividing it into two separable edge interfitting sections, effecting dome and open base ends, a base-closing section detachably engaging the body to separably hold its sections together at its open base end, air venting and dispensing

35 punches, respectively, interposed between the sections at the dome end and removably socketed therein at confronting edges of the body sections when interfitted to each other, and a pouring spout common to the dispensing punch and separably interlocking the body sections at the dome end of the body.

2. A device of the kind described, comprising a central longitudinally split container-receiving body dividing it into two separable edge interfitting sections, effecting dome and open base ends, a base-closing section detachably engaging the body to separably hold its sections together at its open base end, air venting and dispensing punches, respectively, interposed between the sections at the dome end and removably socketed therein at confronting edges of the body sections when interfitted to each other, a pouring spout common to the dispensing punch and separably interlocking the body sections at the dome end of the body, and slack absorbing means 20 confined in the base section and bridging the meeting edges of the body sections when interfitting each other.
